SASH FASTENER

Filed May 24, 1927

Inventor:
August F. Schmidt,
of Jersey City, New Jersey.
A. D. 1875.

UNITED STATES PATENT OFFICE.

AUGUST F. SCHMIDT, OF ST. PETERSBURG, FLORIDA.

SASH FASTENER.

Application filed May 24, 1927. Serial No. 193,792.

This invention relates to sash fasteners for windows and the like and aims to produce a novel fastener that will lock both sash in closed position and also in partly open position and thus provide greater security against the opening of sash by thieves and burglars.

In the drawings of one embodiment of my invention described and illustrated herein, 10 Fig. 1 is a plan, partly broken out for convenience, showing the bolt in unlocking position;

Fig. 2, a similar view with the bolt in locking position;

15 Fig. 3, a similar view on a smaller scale showing the fastener on a sash and in unlocking position;

Fig. 4, a similar view with the bolt in locking position;

20 Fig. 5, a cross-section detail on the line 5—5, Fig. 1;

Fig. 6, a plan of the fastener in adjustable locking or ventilating position; and

25 Fig. 7, a partial elevation of two window sash, partly open and locked with my novel fastener.

Referring first to Figs. 1, 2, my novel fastener comprises a base plate 1 of suitable size and material, as metal, provided with apertures 2, for receiving screws to secure the plate to the top of the lower sash 22, Fig. 3.

The inner end of the plate, Figs. 1, 2, which overlaps the inner edge of the sash has an eye 3 while the opposite and outer end carries a housing 4 fashioned to provide two curved tongues or fingers 5, 6, bent upwardly and inwardly from the edge of the plate and constituting bolt and handle stops herein-after referred to, for the handle and bolt.

40 A bolt operating handle 7, Figs. 1 to 4, herein in the shape of an elongated bail or loop, has one end curved downwardly and laterally, engaging the eye 3, and its opposite end provided with a bolt, or, as in this case, by 45 being bent outwardly under the housing 4, to form the bolt 8.

The plate 1 is provided centrally with two laterally extended, upstanding and spaced ribs 9, 10, which act as a detent and a withdrawn bolt stops respectively for the handle 7 at opposite sides thereof. The handle 7, Fig. 1, is provided at a point near the bend forming the bolt with a flattened or grooved

section 11 which enables the bolt end of the member 7 to be slid longitudinally, Figs. 1, 55 2, beneath the fingers or stops 5, 6, in assembling.

The parts being assembled as in Figs. 1 to 4, the plate is secured to the top of the lower sash near the edge thereof with the handle 60 lying down upon the sash and the free side of the handle member between stops 9, 10, Fig. 1. A plurality of holes 12 are drilled in the front face of the side stile 13 of the upper sash 14, Fig. 3, sufficiently deep to receive the bolt 8 65 when in described and locking position. Preferably a short piece of metal tubing large enough to receive the bolt 8 is then driven into each hole 12 to prevent the hole from being enlarged by the action of the bolt in entering 70 and withdrawing from the hole.

When the sash are both closed, Fig. 4, and it is desired to lock them, the handle 7 is raised upright until its resiliency frees it from the rib or withdrawn bolt stop 10, then is lowered 75 until it is substantially parallel with the top of the lower sash 22 when it spreads, owing to its resiliency, and the bolt 8 slides outwardly beneath the fingers or stops 5, 6, and into the aperture 12, when the handle is again 80 raised to position, Fig. 2, and left to rest behind the ear 15 on handle stop 6.

In this position it will be clear that the sash are both locked against upward or downward movement, and no knife blade or the like slid up between the two sash could be used to throw the bolt 8 laterally to unlock it, nor could the bolt be worked backwardly and withdrawn from the aperture 12 because of the withdrawn bolt stop 5.

If it is desired to leave the fastener so that either sash or both can be opened part way for ventilation only or in adjustable locked position, then after the bolt 8 has slid into the hole 12 the handle 7 is not raised as described, but is left lying on top of the lower sash, in adjustable locking and ventilating position, Fig. 6.

Now if either sash or both are moved part way, the movement of one sash relative to the other will cause the bolt 8 to turn in its housing and against the corner of the slit 23 of the plate 1 as a fulcrum and the handle 7 to rise upright and slide in the groove 23, permitting the lower sash to slide upward between the sides of the handle 7, to a distance

equal to the length of the handle, see Fig. 7, thus preventing further movement of either sash. When the sash are closed the handle will automatically drop back to position 5 shown in Fig. 6.

Neither sash, however, can be moved a greater distance than the length of the handle permits, the handle being made of desired length with this feature in mind. This feature permits a sash to be raised or lowered a limited distance as desired at night, for instance, or at any time for ventilation, with the assurance, however, that it cannot be moved any further and thus the security of 15 the lock in an adjusted position is also obtained.

This lock is of great convenience on any sash, but particularly for use on sash in bungalows where the sleeping rooms are on 20 the ground floor and where a partly opened window leaves an especially favorable opportunity for annoyance.

This invention is not limited to the precise embodiment thereof described and illustrated.

Claims—

1. A sash fastener comprising a fastener plate, an unlocking bolt stop thereon, a bolt housing having a bolt therein and a handle 30 slot, a handle for the bolt straddling the lower sash when in adjustable locking position, the handle constructed and arranged to swing to an upright position and permit the lower sash to be raised a limited distance.

35 2. A sash fastener comprising a base plate with an unlocking bolt stop thereon, a bolt housing, a bolt therein, a bifurcated handle for the bolt, swingingly mounted in the housing, and constructed and arranged to receive 40 its sash when either sash is moved relative to the other to permit limited movement thereof and locking engagement against unlimited movement.

45 3. A sash fastener comprising a base to be secured to the upper edge of the lower sash, a bolt thereon, with a sash spanning handle and movable in a plane substantially parallel with the sash for operating the bolt.

50 4. A sash fastener comprising a base to be secured to the upper edge of the lower sash, a sliding bolt thereon having a sash spanning, vertically swinging and relatively sliding handle and movable in a plane sub-

stantially parallel with the sash for operating the bolt.

55

5. A sash fastener comprising a base plate to be secured to the upper edge of the lower sash, a bolt housing thereon, a withdrawn bolt stop on the plate, an extended bolt stop thereon, and a handle stop on the housing.

60

6. A sash fastener comprising a base plate to be secured to the upper edge of the lower sash, a handle pivoted thereto, a bolt housing thereon, a slidable bolt thereon, a detent and a withdrawn bolt stop thereon and an extended bolt stop also on the plate.

65

7. A sash fastener handle with a bolt forming end thereon and a housing therefor with a handle channel thereunder, and a groove on the handle substantially parallel with but 70 in a different vertical plane from the bolt to permit adjustment of the handle relative to the housing.

75

8. A sash fastener comprising a base plate to be secured to the upper edge of the lower sash, a withdrawn bolt stop thereon, a bolt housing having a passage thereunder for the movement of a handle, and an extended bolt stop, and a handle stop also on the housing.

80

9. A sash fastener comprising a base plate to be secured to the upper edge of the lower sash, a bolt thereon to engage an upper sash, and having a handle, the bolt pivoted to the base to lie flat thereon and on the sash when the sash is unlocked and when adjustably locked, the handle standing upright when the sash is positively locked.

85

10. A sash fastener comprising a base to be secured to the upper edge of the lower sash, a bolt thereon with a sash spanning handle to actuate it, and having a sliding engagement with the base to permit the sash and base to slide upward between the side members of the handle for adjustment of the sash within a limited distance.

90

11. A sash fastener comprising a base, a bolt thereon with a handle multi-member for operating the bolt and having a pivoted and sliding engagement with the base whereby when the bolt is extended, the sash may slide between the two side members of the handle to permit adjustment of the sash in its frame when locked against unlimited movement.

95

In testimony whereof, I have signed my name to this specification.

AUGUST F. SCHMIDT.
